United States Patent Office

Des. 179,386
Patented Dec. 11, 1956

179,386

DISHWASHER UNIT FOR SINKS

George Graff, Toledo, Ohio, assignor to Gerity-Michigan Corporation, Adrian, Mich., a corporation of Michigan

Application July 25, 1955, Serial No. 37,109

Term of patent 14 years

(Cl. D91—3)

Fig. 1.

Fig. 2.

BY

FIG. 3.

FIG. 4.

Fig. 1 is a front perspective view of a dishwasher unit for sinks embodying my new design;

Fig. 2 is a top plan view of the new design;

Fig. 3 is a front elevational view thereof; and

Fig. 4 is an end elevational view.

The dominant feature of the design resides in the portions shown in full lines.

I claim:

The ornamental design for a dishwasher unit for sinks, substantially as shown and described.
